UNITED STATES PATENT OFFICE

EDWARD BRUNHOFF, OF WYOMING, OHIO, ASSIGNOR TO THE ARNOLD ELECTRIC COMPANY, OF RACINE, WISCONSIN, A CORPORATION OF WISCONSIN

POWDER-DISPENSING APPARATUS

Application filed December 5, 1925. Serial No. 73,517.

My invention relates to improvements in powder dispensing apparatus. One of its objects is to provide improved means to dispense merchandise in pulverulent form, as for instance, at drug stores and soda fountains. Another object is to provide improved means, to regularly dispense substantially uniform volumes of the articles to be dispensed. Another object is to provide improved means to hold and feed the articles to be dispensed to the measuring and dispensing apparatus. Another object is to provide improved means to catch and hold the articles delivered from the measuring and dispensing apparatus in a delivery hopper and to discharge the same when required into a glass, or other container presented to the delivery hopper to receive the same. Another object is to provide an improved supporting container for the dispensing apparatus. My invention also comprises certain details of form and arrangement, and combination of components, all of which will be fully set forth in the description of the accompanying drawings, in which:

Fig. 1 is a side elevation of a powder dispensing apparatus embodying my invention.

Fig. 2 is a front elevation of the same.

Fig. 3 is a horizontal section through the same taken on line 3—3 of Fig. 1.

Fig. 4 is a vertical sectional view taken on line 4—4 of Fig. 3.

Fig. 5 is a sectional view taken on line 5—5 of Fig. 4.

Figs. 6 and 7 are perspective views of the powder feeding and measuring spider.

Fig. 8 is a perspective view of the actuating ratchet wheel detached.

Fig. 9 is a perspective view of the actuating lever and pawl detached.

Fig. 10 is a side elevation of the powder agitating member detached.

Fig. 11 is a perspective view of the ratchet wheel engaging stop plunger detached.

Fig. 12 is a perspective view of the delivery hopper door detached.

Fig. 13 is a perspective view of the spider cover plate detached.

Fig. 14 is a side elevation of the actuating shaft detached.

The accompanying drawings illustrate the preferred embodiment of my invention in which 15 represents the supporting standard having a relatively wide base 16 recessed beneath the delivery hopper at 81 to provide ample room to introduce a glass or other container beneath said hopper. The base 16 is, preferably, provided upon its under face with a series of soft rubber vacuum cups or suckers, 18, to serve as a soft or cushioned support for the base resting upon the smooth upper face of a show case or counter, and at the same time to act automatically to hold the base more firmly in place to thereby resist accidental or other pressure tending to upset the dispensing apparatus.

Mounted upon the standard 15 is a casing 19 having a chamber 20 in which is mounted the actuating mechanism, a delivery hopper 21, and an upwardly open chamber 22, in which is mounted the dispensing apparatus. A tubular receiving hopper 24, preferably of sheet metal, is detachably and telescopically attached to the open mouth of the chamber 22. A lid 25 preferably provided with a transparent panel or window 26 is hinged to the upper end of the receiving hopper 24, and locked in closed position by means of a spring latch member 27. The side and bottom walls of chamber 22 are composed of one piece of material 28; the side and bottom walls of the chamber 20 of another section of material 19, and the delivery hopper 21 of another section of tapered tubular outline. The bottom wall of the section 28 is provided with a discharge port 30, leading from the cylindrical lower portion of the chamber 22 to the upper end of the delivery hopper. The section 19 is provided with inwardly directed projections 32 to which the section 28 is detachably held by means of counter-sunk screws 33 passing through the bottom of section 28 and threaded into the projections 32. The delivery hopper is provided with side projections 34 which are detachably attached to the section 19 by means of screws 35, to hold the delivery hopper in place.

A short vertical shaft 40 is journaled at its lower end to the section 19 and at an intermediate point, is journaled in a journal box or 100

perforation in the bottom of section 28. A laterally projecting pin 39 above the floor of section 28 limits the downward movement of the shaft 40. A measuring and dispensing spider has a hub 41 to fit detachably upon the upper end of shaft 40 within the lower cylindrical portion of chamber 22 and radially directed arms 42 extending into close contact with the inner face of the cylindrical wall portion of member 28. The spider hub 41 has a recess 43 to receive the projecting portion of the pin 39 to thereby lock the hub 41 and arms 42 to the shaft 40 and cause them to revolve with the shaft 40.

Within the chamber 20 a ratchet wheel 44 is mounted rigidly upon the shaft 40. The ratchet wheel periphery is provided with a series of teeth 45 and interposed flat or plane sections or spaces 46. A spring actuated 20 plunger having an enlarged flat or plane faced head 47 is mounted to move endwise in a perforated boss 48 projecting inwardly from the casing 19 and is resiliently energized by a coiled spring 49 interposed between the head of the plunger and the inner face of casing 19. The outer plane face of the plunger head 47 bears yieldingly upon the periphery of the ratchet wheel and serves to always bring the ratchet wheel 44 and shaft 40 to predetermined and uniformly spaced 30 positions of rest relative to the casing 19, due to the head 47 of the plunger, after the passage across its face of each ratchet tooth springing back into position to engage the plane face of the plunger head with a plane face on the ratchet wheel and thereby forcing the ratchet wheel 44, the shaft 40, and the spider hub 41 and arms 42 to assume one or another of a series of uniformly spaced 35 and predetermined positions, with one pair of the spider arms registering upon opposite boundaries of the delivery port 30 leading from the chamber 22 to the delivery hopper.

An actuating lever 51 is loosely journaled upon the shaft 40 adjacent to the ratchet wheel and has pivotally attached thereto a pawl 50 in position to engage successively the teeth of the ratchet wheel and feed the ratchet wheel and shaft 40 forward step by step as the actuating lever 51 is rocked forwardly and backwardly upon the shaft 40. A grasshopper type of spring 52 holds the pawl in position to engage the ratchet teeth and another grasshopper type of spring 53 serves to move the actuating lever backwardly after each forward movement of said lever under the hand of the operator. The free end of the actuating lever 51 extends through a slot 53' in the side of the casing 55 19 in position to be grasped by an operator.

Within the chamber 22 and above the spider members 41 and 42, and opposite the delivery port 30 is a plate 55 which has a series of spurs or projections 56 entering corresponding recesses in the inner face of the

casing 28 to hold the peripheral portion of said plate 55 in place relative to the casing member 28. The central portion of the plate 55 is perforated for the passage of the upper end of the shaft 40, and seats upon or around a cylindrical shoulder 57 at the upper end of the spider hub 41 which serves to retain the central portion of plate 55 in place and also to form a journal support for the upper end of the hub 41 and shaft 40. The plate 55 prevents the passage of the powder directly from the receiving hopper in the port 30, but provides for the powder to be fed by the spider arms 42 from the chamber 22 laterally to a position beneath the plate 55 where it is discharged through the port 30 into the discharge hopper. An agitator 58 is secured to the reduced upper end of the shaft 40 by means of a left hand threaded nut 59 carried by said agitator, screwed down upon the reduced upper end of the shaft 40 against a shoulder at the base of said reduced section. The agitator thus also locks the central portion of the plate 55 against movement upwardly. The agitator rotates with the shaft 40 and is provided with a series of upwardly directed and staggered fingers which serve to scrape the powder from the upper portion of the walls of chamber 22, and to loosen and feed the powder downwardly within the receiving hopper into the spaces between the spider arms 42 so as to fill said spaces and deliver substantially uniform volumes of powder at each movement of the actuating lever.

A door or plate 60 closes the lower end of the discharge hopper 21, being hinged at 61 to the exterior of said hopper 21, and held normally in closed position by means of a grasshopper type of spring 62. The plate 60 is provided at opposite sides thereof with downwardly directed projections 63 positioned and adapted to be engaged by the upper edge of a glass or other open mouthed container 64, and shifted thereby from a closed to open position as shown in full and dotted lines Fig. 1, and serving to depress the plate 60 into the upper end of the container 64, so as to guide and discharge the contents of the discharge hopper 21 into the container 64. The actuating lever may thus be actuated at or previously to presenting the container 64 to the plate 60 and projections 63.

The base 16 is of considerable weight preferably having an extra or separately weighted member 74 housed within a relatively thin shell 73 constituting an integral lower extension of the standard 15, adapted to be polished and electroplated, or otherwise exteriorly finished. The members 19, 15, 74 and 73 are adapted to be detachably assembled, and clamped together by means of a bolt 71 and nut 72, see Fig. 1. The weight of the base in conjunction with the rubber vacuum cups, 18, serve to rigidly hold the

apparatus in place so as to effectually resist any normal strain tending to release or upset the apparatus, and without liability to injure the smooth-faced counter or other article serving as a support therefor.

5 The apparatus herein illustrated and described is capable of considerable modification within the scope of the claims, without departing from the spirit of my invention.

10 What I claim is:—

1. Powder dispensing apparatus comprising a powder receiving chamber having a discharge port through its floor at one side thereof, a vertically disposed actuating shaft extending through and partly above the floor of said chamber, a powder measuring and feeding member detachably mounted upon said shaft within and resting upon the floor of said chamber and rotatable with said shaft, a substantially horizontal plate located stationarily above a portion of said measuring and feeding member and vertically above said discharge port, an actuating ratchet wheel mounted rigidly upon said shaft below the floor of said chamber, a manually operable lever provided with a pawl to engage the teeth of said ratchet wheel to intermittently feed said shaft and measuring and feeding member rotatably in one direction, and a resiliently actuated plunger held yieldingly in engagement with said ratchet wheel to check rotation of said shaft in either forward or reverse direction at predetermined positions of said shaft.

35 2. Powder dispensing apparatus comprising a powder receiving chamber, a powder measuring and feeding member operable to intermittently feed powder from said chamber, a powder delivery port, manually operable means to intermittently actuate said measuring and feeding member, a stop member rotatable with said measuring and feeding member and provided with a plurality of plane faces corresponding to the stop positions of said feeding member, and a resiliently actuated plunger in position to yieldingly successively engage said plane faces to predetermine the stop positions of said measuring and feeding member, independently of variable amounts of energy applied to said actuating means.

50 3. Powder dispensing apparatus comprising a powder receiving chamber having a discharge port through its floor at one side thereof, a vertically disposed actuating shaft extending through the floor of said chamber, a powder measuring and feeding member resting upon the floor of said chamber and adapted to be rotatably driven by said shaft, a substantially horizontal plate above a portion of said measuring and feeding member and stationarily mounted relative to said receiving chamber, said plate being located vertically above the chamber discharge port, 65 a ratchet wheel to rotate said actuating shaft

provided with a series of ratchet teeth and interposed plane faces, a plunger having a head to contact with the plane faces of said ratchet wheel and to yield and ride over the teeth of said ratchet wheel, means to yieldingly hold said plunger in contact with the periphery of said ratchet wheel, and a manually operable lever provided with a pawl to engage the teeth of said ratchet wheel to intermittently feed said ratchet wheel and shaft forward a fraction of a revolution, said plunger acting upon the plane faces of said ratchet wheel in both forward and reverse direction to bring said ratchet wheel and measuring and feeding member uniformly to predetermined positions of rest.

70 75 80 In testimony whereof I have affixed my signature.

EDWARD BRUNHOFF.
